UNITED STATES PATENT OFFICE

2,630,252

SLEEVE STRETCHER

Anna Ottoson, New York, N. Y.

Application June 1, 1949, Serial No. 96,483

2 Claims. (Cl. 223—74)

1

This invention relates to an improved means for smoothing and drying ruffled sleeves.

In that type of dress for ladies and children which has ruffled and puff sleeves, the problem of ironing and smoothing out the puffs and ruffles is such that a very smooth job is difficult to attain, and where the puffs are formed of sheer material a hot iron frequently scorches the material. It is, therefore, an object of this invention to provide means whereby the puffs and sleeve bands may be smoothed out in a manner to eliminate wrinkles and with such means incapable of scorching the fabric. In the carrying out of this invention, an expansible ring is inserted into the puff so that the puff will be held taut, and a band expander is inserted into the band. The puff and band are preferably damp at the time of insertion of the expanding members, and the puff and band are then permitted to dry while under the tension of the expanding members.

With the above and other objects in view, my invention consists in the arrangement, combination and details of construction disclosed in the drawings and specification, and then more particularly pointed out in the appended claims.

In the drawings,

Figure 1 is a plan view of a sleeve smoothing device constructed according to an embodiment of this invention,

Figure 2 is an edge view of the device,

Figure 3 is a plan view of a sleeve band smoothing device,

Figure 4 is a detail front elevation partly in section, showing the sleeve or puff smoothing device and sleeve band smoothing device in applied position.

Referring to the drawings and first to Figures 1 and 2, the numeral 10 designates generally a resilient expandible ring formed of resilient wire. The ring 10 is split and one end thereof is formed into a U 11 projecting inwardly, with one leg 12 of the U 11 having disposed in parallel offset relation with respect thereto an extension 13.

The other end of the wire forming the ring 10 is bent in the shape of a second U-shaped member 14 disposed in parallel relation with the U-shaped member 11, and one leg or side 15 of the U-shaped member 14 has disposed in parallel offset relation with respect thereto an extension 16. The end 17 of the ring 10, which has the U-shaped member 14 formed integral therewith extends through the loop formed between the leg 12 and the extension 13, whereas the end 18 extends through the loop formed between the leg 15 and the extension 16.

2

The U-shaped members 11 and 14 also provide handles or grasping members by means of which the ring 10 may be contracted by moving the members 11 and 14 away from each other. The ring 10 is adapted to be extended into the puff of a sleeve S, as shown in Figure 4, the ring being contracted sufficiently to be slipped through the sleeve band B. After the ring 10 in its contracted form is slipped through the arm hole, the ring is released and will expand to a point where the puff of the sleeve S is stretched. The ring 10 is left within the sleeve until the material has thoroughly dried.

In order to provide a means whereby the band B may also be stretched, I have provided a longitudinally bowed band stretching wire 20 which is formed at the opposite ends thereof with downwardly convergent extensions 21. The extensions 21 are adapted to engage the inner surface of the band B at diametrically opposed points and the extensions 21 merge in obtusely disposed arms 22. The arms 22 have extending therefrom substantially right angular extensions 23 terminating in eyes 24.

The arms 22 comprise handles by means of which the bowed connecting member 20 which connects the band engaging members 21 together may be contracted to provide for slipping of the members 21 on the inside of the sleeve band B. The arms 22 are then released whereupon the bowed connecting member 20 will stretch the band B and when the material has dried, the sleeve band will be in a condition which will not require ironing.

It will thus be readily apparent that the resilient expandible ring 10 serves to stretch the puff of the sleeve in one direction while the stretching device simultaneously coacts therewith to expand the puff in another direction. By virtue of the simultaneous use of both of these devices, a perfectly shaped and formed puff sleeve results, which could be achieved in no other manner.

I do not mean to confine myself to the exact details of construction herein disclosed, but claim all variations falling within the purview of the appended claims.

What I claim is:

1. A sleeve stretching means for a puff sleeve garment comprised of a split annular ring insertible into the puff of the sleeve, and a stretching device coacting with said ring comprised of an integral element including a pair of convergent members connected at their divergent ends by a resilient connecting member for insertion into the band of said sleeve whereby said ring

and said convergent and connecting members coacting hold said sleeve in desired stretched relation, said ring engaging about the convergent ends of said convergent members to limit the stretching effected thereby.

2. A sleeve stretching means for a puff sleeve garment comprised of a split annular ring insertible into the puff of the sleeve, and a stretching device coacting with said ring comprised of an integral element including a pair of convergent members connected at their divergent ends by a resilient connecting member for insertion into the band of said sleeve, and a second pair of convergent members forming handle portions each converging toward the convergent end of one of said first-mentioned pairs of convergent members, whereby said ring and said convergent and connecting members coactingly hold said sleeve in desired stretched relation, said ring en-

gaging about the convergent connected ends of said pairs of convergent members to limit the stretching effected thereby.

ANNA OTTOSON.
